UNITED STATES PATENT OFFICE

2,375,552

TROMMEL

Charles C. Herbert, San Jose, Calif.

Application October 19, 1943, Serial No. 506,909

1 Claim. (Cl. 241—171)

It is one object of the present invention to provide a trommel constructed and arranged to crush the material passing therethrough and to deliver the same in condition for processing on a concentrating table.

It is another object of the invention to provide a device of the character indicated wherein the material operated upon is caused to move continuously through the same and is effectually prevented from wedging or clogging, a clear path of travel for said material being maintained at all times.

It is also an object of the invention to provide a device of the character indicated wherein the dust raised by the operation of the crushing means may be quickly and easily removed.

In this device as now conceived balls are used in the crushing operation, and it is the intent of the present invention to provide means whereby the balls are caused to advance through the trommel together with the material being operated upon, and to cause the automatic return of the balls to the entrance of the trommel after completing a journey through the same, while the said material is discharged at the discharge end.

Finally it is an object to provide a device of the character indicated that will be economical to manufacture, simple in form and construction, strong, durable, and highly efficient in its practical application.

In the drawing:

Figure 1 is a discharge end elevational view of a device embodying my invention.

Figure 2 is a sectional view on line 2—2 of Figure 1, with parts broken away.

Figure 3 is a side elevation of a portion of the receiving end of the ball return chute and the track leading thereto.

Figure 4 is a detail section of a portion of the ball-carrying track.

The structure as disclosed comprises a tubular shell as 1 mounted for rotation in the direction of the arrow 2 by any suitable means not shown.

On the inner side of the shell 1 is formed a helical groove or track as 3 extending from the receiving end of the trommel to its discharge end where it discharges upon a screen as 4 which rotates as a unit with the shell 1.

Axially mounted in the shell 1 through the medium of supporting arms 5 is a hollow conical member 6 having its larger end disposed at the receiving end of the shell 1 and its smaller end at the discharge end of the shell 1, with a tubular member 7 connecting this latter end of

the member with the discharge end of the track 3. This member 7 has a slot 8 formed therein to extend throughout its length in a position to permit material received from the track 3 to be discharged on to the screen 4.

In each annular section of the spiral is placed a ball as 9 of sufficient size and weight to perform its function properly, and in the lower side of the member and at the larger end thereof 10 is formed an opening sufficiently large to permit the passage of a ball therethrough.

At spaced points throughout the length of the spiral track 3 are formed lifting devices such as the platforms or sockets 11, radially arranged 15 relative to the center of the shell 1, and formed in such a manner as to carry a ball 9 upwardly a distance as the shell rotates and then permit it to fall down to the next lower shelf and with crushing force on the material therein. In the 20 drawing six lifters are formed equally spaced about each full turn of the spiral track, but they may be made in any desired number or form and spaced as desired, so the balls may fall at unequal intervals.

25 Assuming the shell 1 to be rotating slowly in the direction indicated by arrow 2 and with the material to be operated upon, such as gold bearing gangue, flowing into the shell 1 at its receiving end from a suitable source of supply 30 as 12, the operation is as follows. All of the balls 9 in the lowermost sockets 11 are carried upwardly as indicated in dotted lines at 13, and then as the shell revolves they roll off of their respective shelves as indicated in dotted 35 lines at 14 in Figure 4, and drop down into the next succeeding socket 11. In the free and unobstructed fall from one socket to the one following each ball acquires sufficient force to crush the material in the socket into which it falls.

40 This trommel is designed to be used particularly in placer mining where much of the gangue consists of clay which requires further breaking down to release the particle or particles of gold 45 which may be entrapped therein, although it may be used equally successfully in the breaking down and cleaning of any other type of ore.

The continuous rotation of the shell 1 in same direction will, of course, cause a continuous forward movement of the balls and the material flowing into the shell, but the continued pounding

50 to which the material is subjected gradually reduces it to very fine state ready to be passed over a concentrating table and the gold removed therefrom. As the crushed and powdered mate-

rial passes from the track 3 to the member 7, the continued rotation causes the said material to fall through the slot 8 to the screen 4 where such larger particles as passed through the shell without sufficient breaking are separated from the crushed and finished material.

Each rotation of the shell will also cause a ball to pass into the member 7 and thence roll to the conical member 6, where it rolls down to the discharge opening 10 and is returned to track 3, and the cycle is repeated.

Obviously, in a structure of the type described the material entering at 12 is kept continually in motion and is effectually prevented from clogging in any point during its path of travel, and the continual stirring which it receives as it flows from one socket to the next permits every portion to be subjected continually to the pounding action of the balls.

A still further advantage of the operation as performed by this machine is that each time the material is pounded in the socket and then poured back into the next socket much of the

lightest and finest dust is momentarily floated in the air and may be easily blown out of the shell.

Having thus described my invention what I claim as new and desire to secure by Letters Patent is:

A structure of the character described comprising, a rotatable hollow cylinder having an annular screen of equal diameter disposed at one end to rotate therewith and having an internal helical groove integrally formed therein with receiving and discharge ends, the discharge end terminating in a conical tube concentrically mounted in the cylinder to rotate as a unit therewith with its larger end terminating at the receiving end of the groove, and said conical tube being provided with an opening at its larger end disposed to discharge balls into the receiving end of the groove, and grinding balls freely movable in the groove, and that portion of the groove merging with the tube being provided with means for discharging crushed material therefrom on to the screen.

CHARLES C. HERBERT.
